UNITED STATES PATENT OFFICE.

ANNIE M. HILLMAN, OF WESTHOFF, TEXAS.

WINDOW-FRAME ATTACHMENT.

1,032,062.

Specification of Letters Patent.

Patented July 9, 1912.

Application filed August 17, 1911. Serial No. 844,590.

To all whom it may concern:

Be it known that I, ANNIE M. HILLMAN, a citizen of the United States, residing at Westhoff, in the county of Dewitt, State of Texas, have invented certain new and useful Improvements in Window-Frame Attachments; and I do hereby declare the following to be a full, clear, and exact description of the invention, such as will enable others skilled in the art to which it appertains to make and use the same.

This invention relates to new and useful improvements in window frame attachments.

An object of this invention is the provision of a pair of bars which may be secured to a window frame, and support adjustably thereon a shade roller of any customary design.

A further object of this invention is the provision of a pair of bars suitably connected at their opposite ends and adapted to be applied to a window frame, the said bars being of such construction that they will support a pair of roller brackets and retain the same against any undesired displacement.

A still further object of this invention is to improve and simplify devices of this character rendering them comparatively simple and inexpensive to manufacture, reliable and efficient in use and readily operated.

With the above and other objects in view this invention resides in the novel features of construction, formations, combinations and arrangements of parts to be hereinafter more fully described, claimed and illustrated in the accompanying drawings, in which:

Figure 1 is a front elevation of a window frame with my attachment applied thereto. Fig. 2 is a vertical sectional view taken on the line 2—2 of Fig. 1. Fig. 3 is a horizontal sectional view taken on the line 3—3 of Fig. 1. Fig. 4 is a similar view taken on the line 4—4 of Fig. 1.

Referring to the accompanying drawings by similar characters of reference, throughout the several views, the numeral 5 designates generally a window frame consisting of the customary vertical side bars 6 connected at their opposite ends by the upper and lower rails 7 and 8. A pair of spaced parallel side bars 9 and 10 are secured to the side bars 6 upon opposite sides of the window opening and are formed at their adjacent edges with ribs or beads 11 located in spaced relation to the faces thereof, to produce between the said ribs or beads and the side rails

6 of the window a T shaped guide opening 12, in which is slidably located upon opposite sides of the window a vertically movable plate 13. The upper ends of said plates 13 have projecting laterally therefrom a pair of roller brackets 14, which extend outwardly between the plates 9 and 10, and support thereon a roller 15, upon which is wound a curtain 16. These plates 13 are provided in a lower terminal with thread apertures 17 through which are extended the threaded shanks of thumb screws 18, adapted to contact with the side member 6 of the window frame, and retain the plates 13 in their various adjustable positions. The roller brackets 14 are connected by a horizontal bar 19 to which may be secured a window curtain for longitudinal movement with respect to the window opening.

Bar 20 connects the upper ends of the plates 9 and 10, and extends through the guide slots 11 in spaced relation from the side members of the window frame as clearly indicated in Fig. 2 of the drawings, and as designated by the numeral 21. A pair of brackets 22 each of which is provided with a roller supporter 23 and a vertical extension 24, is extended in the space at each side of the window by the plates 9 and 10, bar 20, and side members 6, and is held against any undesired lateral displacement by its engagement with the said plates 9 and 10, while the bar 20 accordingly retains the same in spring engagement with the side members 6, which obviously prevents their undesired displacement. The bar 25 which connects the lower ends of the plates 10 is preferably formed in any design which will extend above the lower side of the frame 95 which will serve to prevent a child from falling out of the window. This bar however, will be made plain as desired.

From the foregoing disclosure taken in connection with the accompanying drawings 100 it will be manifest that a window frame attachment is provided for which will fulfil all the necessary requirements of such devices.

Having thus fully described this invention, what I claim as new and desire to protect by Letters Patent, is:

1. The combination with a window frame, of a pair of spaced bars, secured to the opposite sides thereof, bars connecting the said 110 space bars, plates slidable between the spaced bars, shade roller brackets secured to the

sliding plates, and brackets located between the spaced bars, and engaging one of said connecting bars substantially, as and for the purpose set forth.

- 5 2. The combination in devices such as described with the opposite sides of a window frame, a pair of bars secured to each side member of the said frame, and extended in spaced parallel relation to each other, said 10 bars being provided at their adjacent outer edges with ribs producing guide spaces between said bars, and side members of the window frame, plates slidable between the bars, brackets supported upon the plates,

means for retaining the plates in their adjustable positions, bars connecting opposite ends of the spaced bars, and brackets located between the spaced bars, and engaging at opposite sides thereof, and clamped against the side members of a window frame, by the 15 adjacent connecting bars, as and for the purpose set forth.

In testimony whereof, I affix my signature, in presence of two witnesses.

ANNIE M. HILLMAN.
